MECANIQUES, OF IVRY-PORT, SEINE, FRANCE.

APPARATUS FOR SETTING GAGES.

1,379,878.

Specification of Letters Patent. Patented May 31, 1921.

Original application filed December 28, 1917, Serial No. 209,331. Divided and this application filed February 21, 1919. Serial No. 278,439.

To all whom it may concern:

Be it known that I, LOUIS ROUANET, citizen of the Republic of France, residing at 42 Rue Franklin, Ivry-Port, Seine, in the 5 Republic of France, have invented new and useful Improvements in Apparatus for Setting Gages, of which the following is a specification.

This invention relates to an apparatus 10 especially designed in order to allow of adjusting the dimensions of space gages of the kind described in my co-pending application for Letters Patent Serial No. 209,331 filed on December 28, 1917, of which the 15 present application is a division. This apparatus is constructed for making adjustment of a whole series of gages with regularly varying dimensions for instance from centimeter to centimeter and to this end it is 20 made up of two sliding pieces which take a longitudinal movement upon a common base. One of these pieces can move along the length of the base or table and can be fixed on the latter by a suitable device and 25 in any one of the positions which are laid out in accordance with the dimensions of the gages belonging to the series in question; while the other sliding piece is movable in a less degree and can only be displaced by the 30 action of a micrometer device and this within the limits corresponding to the difference in dimension between any one of the two gages which follow each other in the series, i. e. the said sliding piece is not displaced 35 more than one centimeter, in the above example. Each of these sliding pieces is bored to receive a cylindrical plug, containing an eccentric hole whose diameter corresponds to that of the rods which are used 40 for the gage, and each of these holes is designed to receive one of the said gage rods when performing the operation of adjustment. The holes in the plugs are so disposed as to allow of adjusting the initial distance 45 parallel to the axis of the table of the apparatus.

In the accompanying drawing,

Figure 1 is a longitudinal section on line A—A of Fig. 2 of the adjustment apparatus constructed according to the present 50 invention, and showing a space gage in position to be adjusted.

Fig. 2 is a plan view of the same apparatus the space gage being removed.

Fig. 3 is a cross section on line B—B of 55 Fig. 1.

The apparatus shown in the drawing is composed of a fixed table or base 1 containing two sliding pieces 2 and 3 adapted to move thereon. The sliding piece 2 carries two holes 11 disposed symmetrically about the axis of said piece. This latter is adapted to slide as far as the end of the table 1 and to be held fixed upon it by means of a pin 4 passing through one of the holes 65 11 and entering one of the holes 5 formed in a staggered relation in the said table. The sliding piece 3 can only be moved by means of the micrometer device, one part of this latter being mounted upon the table while 70 the other part is attached to said sliding piece.

Each of the sliding pieces is bored in order to receive a cylindrical plug 6 provided with a hole 7, which is eccentrically located with 75 respect to the axis of the said plug, each of said plugs 6 being originally disposed in its seat in such manner that the distance between the axes of the holes 7 has exactly the 80 desired value, the line 8 passing through the centers of the holes 7 being moreover parallel to the axis of the table but at a short distance from the latter. When the plugs 6 have been thus set in constructing the apparatus, each of them is clamped to its sliding 85 piece by the use of a small plate 9, bearing against a lateral flat surface on the corresponding plug and having an appropriate width. The holes 7 are adapted to receive 90 the cylindrical ends of the rods *a* *b* of the space gage *c*.

As described in my companion application above referred to, the rods *a*, *b* are eccentrically mounted in the gage *c* and may be clamped in any desired angular position 95 by means of the nuts *d*. The distance between the cylindrical ends of the rods *a*, *b*, may thus be adjusted as desired, within a predetermined range for instance 10 millimeters whereby a gage of any desired dimension may be obtained within the predetermined limits.

The central rod of the micrometer is attached by the pin 12 to the sliding piece 3, and slides within a bearing 13 mounted in 105 fixed position on the end plate 14 which is attached to the table 1 for instance by means of a bolt 14^a. The bearing 13 is mounted

upon plate 14 by means of the nut 15. Between the shoulder 17 of the bearing 13 and the end plate 14 is held the tubular piece 16 which is graduated over a length at least 5 equal to the distance between any two of the holes 5. The thimble 18 which is graduated at the periphery on the slightly conical portion, is split at its other end 19 and provided with a slightly conical internal thread 18^a 10 upon a certain length in order to form a nut which fits without play upon the threaded end of the rod 10. Any looseness in the mounting is prevented by a small nut 20 screwed upon the slit end of the thimble 18. 15 Upon the thimble 18 is screwed the milled cap 21 used to operate the micrometer, and into the interior of the thimble is driven a small ring 22 which should come against the part 17 before tightening up the nuts *d* of 20 the gage *c*.

The holes 5 in the table 1 are spaced on a system of units, for instance with spacing of one centimeter apart, and the different gages to be adjusted are of corresponding dimensions. The pin 4 is disposed so as to fix the sliding piece 2 upon the table 1 for the adjustment of the smallest gage; supposing this gage to be of 20 millimeters size, if it is to be adjusted for verification work upon 25 cylinders of 25 millimeters, this is carried out by turning the milled cap 21 so as to bring the zero of the scale on thimble 18 opposite the mark 5 of the scale on the tubular piece 16. The distance from axis to axis 30 between the holes 7 is thus 25 mm. and by inserting the cylindrical ends of the rods *a*, *b* of the gage into said holes and clamping the rods *a* *b* by means of the nuts *d*, a 25 mm. gage will be obtained. 35

40 If, for instance, a 31 mm. gage is desired, the gage of the next upper size, ranging from 30 to 40 mm. will be taken and adjusted in the same manner as above described, the sliding piece 2 being set by 45 placing the pin 4 in the next hole of the series 5. It is readily understood that the micrometer should be adapted to separate the two sliding pieces by a distance at least

equal to the difference between two succeeding gage values. The same method is employed for all other gage values and for all intermediate dimensions lying between them. 50

Having now described my invention, what I claim as new and desire to secure by Letters Patent is:

1. An apparatus for adjusting the dimensions of space gages comprising in combination a table or base, two sliding pieces movable upon said table each of them having a hole, a plug provided with a hole eccentric 60 to its axis and mounted in each of said holes in the sliding pieces, the said holes of the two plugs being adapted to receive the ends of the contact rods of the space gage, means for holding one of said sliding pieces in a 65 fixed position on the table, and a micrometer screw mounted on the table and adapted to displace the other sliding piece along said table, substantially as described and for the purpose set forth. 70

2. An apparatus for adjusting the dimensions of space gages comprising in combination a table or base provided with holes separated one from each other equal distances, a sliding piece movable upon said table and having a hole adapted to receive a plug and other holes adapted to register with the holes of the table, a second sliding piece movable upon said table and provided with a hole, a plug provided with a hole eccentric to its axis and mounted in each of the corresponding holes of the sliding pieces, the said eccentric holes in the plugs being adapted to receive the contact rods of a space gage, a pin adapted to be passed through 80 one of the holes of the first sliding piece and introduced at the same time in one of the holes of the table for holding said sliding piece into a fixed position, and a micrometer screw mounted on the table and adapted to 85 displace the other sliding piece along said table, substantially as described and for the purpose set forth. 90

In testimony whereof I have signed my name to this specification.

LOUIS ROUANET.
